Thomas H. Whitley, Esq., Secy.

Letters Patent.

The schedule referred to in these Letters Patent and making part of the same, containing a description in the words of the said Thomas H. Whitley himself of his improvement in making dashes and glass bases."

It all to whom these presents shall come.

Be it known that I, Thomas H. Whitley of the town of Paterson County of Essex and State of New Jersey, have invented a new and useful improvement in the manufacture of dashes and glass bases, and the following is a correct description of the said improvement invented by me. In the drawing accompanying this specification, it is a finished dash, A.B.B. are grooved bars into which the glass is put. C.C. are end views of the bottom and top rails of the improved dash through which in the dovetailed groove a sliding bar C is made to slide or strike out to admit the glass and then close again. It is of bolted, twisted or other material to be inserted in the groove to make the glass air tight. It is a dash or short base frame horizontally placed, one directed in like manner to the perpendicular dash. It is a representation of the sliding or lifting bars partly drawn out to show in what manner the glass is introduced into them dash. It is a shifting or portable top and bottom rail to be used when the dovetailed bar is not so admissible.

What is claimed is my new invention and not previously known in the slide and double rail at the top and bottom of the dash and the insertion of a rotten or linentment between the wood and glass to make it air tight.

Witnessed,
Elisha D. Clark,
Henry Whitley,
22 State St.
